UNITED STATES PATENT OFFICE.

WILLIAM C. F. STÜCKEL, OF ROCKAFELLER, ILLINOIS.

GRINDING-MACHINE.

SPECIFICATION forming part of Letters Patent No. 415,886, dated November 26, 1889.

Application filed July 3, 1889. Serial No. 316,431. (No model.)

To all whom it may concern:

Be it known that I, WILLIAM C. F. STÜCKEL, a citizen of the United States, residing at Rockafeller, in the county of Lake and State 5 of Illinois, have invented a new and useful Improvement in Grinding-Machines, of which the following is a specification.

My invention relates particularly to improvements in emery grinding-machines, and 10 more especially to machines of this class which are designed to be used for general work—as for sharpening tools of all kinds, polishing small surfaces, and the like.

The different degrees of hardness of the 15 metals to be ground and the various kinds of work to be performed by the grinding-machine necessitate the employment in a shop of emery or corundum wheels of different degrees of coarseness as to grain and hardness 20 as to texture; and the grinding-machines of the class to which this invention relates, hitherto in general use, have been arranged to hold either one or two adjustable and removable grinding-disks at a time, which had 25 to be removed from the machine whenever the work to be done necessitated the employment of a disk of different grain or texture and replaced by the one required. In a busy shop, where the grinding-machine is more or 30 less constantly in use, the frequent changes of the grinding-disks that have to be made, for the reasons stated, cause delays which are both annoying and expensive; and it is my object to overcome this objection by providing 35 an emery grinding-machine of the above class wherein any one of a number of differently-constituted grinding-disks may be brought into operative position without appreciable delay. It is further my object to 40 provide such a machine of peculiar and improved construction, which will render it economical to manufacture, compact, durable, and otherwise desirable.

To the above ends my invention consists 45 in the general and specific construction and combination of parts, substantially as claimed.

In the drawings, Figure 1 is a top plan view of an emery-grinding machine of my improved construction; Fig. 2, a vertical sectional view 50 of the same, showing parts in elevation and with other parts left out to avoid confusion.

A is the table of the machine, comprising

the legs *t* and the double top B B'. Below the table is a power-shaft C, provided with the fast and loose pulleys C' and driving-pulley C². Above the pulley C² the table is provided with an opening *s*, extending through both tops B B'. Surrounding the opening *s*, and rigidly secured upon the top B', is a flanged ring D, having the inner peripheral 55 rectangular surface *r*, affording a socket, and the outer peripheral groove *r'*.

E is a rotatory annular support in the form of a short cylinder, having a flange E' at its top and resting at its base loosely in the 60 socket afforded by the surface *r* of the ring D. Around the outer circumference of the support E and secured thereto is a series of short brackets or fingers *q*, which extend over the surface of the ring into the groove *r'* and 65 serve to secure the support E without interfering with its rotation in the ring D. On its inner circumference the support E carries a series of brackets F, preferably of the form shown, which extend upward with their free 70 ends in the plane of the surface of the ring E', and afford bearings *p'* for radially-disposed spindles G, which extend toward their opposite ends through bearings *p*. Each 75 spindle G is provided between its bearings *p* 8c *p'* with a pulley G', and toward its outer free end it has a fast flange *o*, against which a grinding-disk Z may be placed and held in position by a collar *o'* and nut *o''*, all in a common manner.

The machine may be constructed with any 85 desired number of spindles G, and each spindle should carry a differently-constituted grinding-disk. In the machine illustrated in the drawings eight spindles are shown, which 90 will serve to hold as many different grinding-disks as would ordinarily be found necessary. When it is desired to use a certain disk of the set, the support E is turned to cause the spindle carrying the required disk 95 to extend above the opening *s*, whereby its pulley G' is directly above the driving-pulley C². The driving-belt H, which runs over the pulley C², is then slipped over the pulley G', when the grinding-disk will rotate with 100 the turning of the shaft C.

The tops B B' are hinged together at *n*, and toward their opposite ends is a rock-shaft *m*, journaled in the top B. The rock-shaft *m* is

provided with a crank m' and carries one or more cams m^2 , which extend against the under side of the top B' , for the latter to rest upon, and which operates with the rocking of the shaft m to raise or lower the top B' . When the top B' is raised, it also raises the support E , which produces tightening of the belt over the pulley G' . Adjacent to the operative position of the pulleys G' is a loose pulley l on a fixed standard l' , secured to the top B , and connected with the rock-shaft m is the automatic belt-shifting mechanism I, comprising a crank-arm k , rigid upon the rock-shaft m , a horizontally-disposed rod k' , pivotally connected at one end to the end of the crank-arm and similarly connected at its opposite end to a bent rod or frame i , extending vertically then laterally in a horizontal direction through a guide-opening (not shown) in the standard l' . On its horizontally-extending portion the rod i carries pins i' , which project on opposite sides of the belt. To slacken the belt H and disengage the pulley G' , the crank m' is turned to rock the cam or cams m^2 to the right, which lowers the top B' and causes immediate slackening of the belt. Further turning of the crank rotates the arm k , which forces along the rods k' and i , causing the latter to slide through its guide-opening in the standard l' and carry with it the belt, causing the latter at the end of the operation to rest upon the pulley l , which is in the plane of the pulley G' when the top B' is lowered. The initial movement of the crank-arm k being in a downward direction, the shifting of the belt does not commence until the latter is slackened. When the belt is thus removed from the pulley G' , the support E may be turned to bring another grinding-disk into position, when by turning the crank m' to raise the top B' again the belt H , with the first movement of the arm k , is shifted upon the new pulley G' .

To fasten the support E when a grinding-disk is brought into operative position and prevent its being turned by the pressure brought to bear against it by the article which is being ground, I provide a pivotal latch on the top B' , which may be caused to engage projections h' on the rotatory support below each spindle G .

It is too obvious to require illustration that the form of gearing between the driving-power and grinding-disk spindle may be changed from that shown, and that the power may be above instead of below the spindles. These variations and others as to details of construction are regarded as being included within the spirit of my invention.

60 What I claim as new, and desire to secure by Letters Patent, is—

1. In an emery grinding-machine, the combination of a fixed support, a rotatory support on the fixed support, a fixed power-shaft and driving-pulley, and a series of spindles, each carrying a grinding-disk, and belt-pulley mounted on the rotatory support and

adapted to be connected in turn to the driving-pulley, substantially as and for the purpose set forth. 70

2. In an emery grinding-machine, the combination, with a fixed support and with a fixed power-shaft and driving-pulley, of a rotatory support mounted upon and above the fixed support, and a series of horizontally-disposed spindles journaled on the rotatory support, carrying grinding-disks and belt-pulleys and adapted to be separately brought into line with the driving-pulley by turning of the rotatory support and belted to the driving-pulley, substantially as and for the purpose set forth. 75 80

3. In an emery grinding-machine, the combination of a fixed support having the raising and lowering top B' , provided with an opening s through it, a power-shaft carrying a driving-pulley below the opening s , a rotatory support upon the top B' about the opening s , and a series of horizontally-disposed spindles journaled on the rotatory support, 85 carrying grinding-disks and belt-pulleys and adapted to be separately brought into line with the opening s by turning of the rotatory support, and belted to the driving-pulley through the said opening, the slackening and 90 tightening of the belt being effected by the lowering and raising, respectively, of the top B' , substantially as and for the purpose set forth. 95

4. In an emery grinding-machine, the combination of a fixed support, a ring D on the fixed support, a rotatory support mounted on the ring D , a fixed power-shaft and driving-pulley, and a series of spindles each mounted on the rotatory support and carrying a grinding-disk and belt-pulley and adapted to be connected in turn to the driving-pulley, substantially as and for the purpose set forth. 100 105

5. In an emery grinding-machine, the combination, with a fixed support and with a fixed power-shaft and driving-pulley, of a rotatory support mounted upon the fixed support, a series of horizontally and radially disposed spindles journaled on the rotatory support, carrying toward their outer ends 110 grinding-disks and toward their inner ends belt-pulleys G' and adapted to be separately brought into operative position in line with the driving-pulley by turning of the rotatory support, and to be connected in turn at their 115 pulleys G' by a belt H to the driving-pulley, and a support l , adjacent to the operative position of the spindles to hold the belt H when it is not connected with a pulley G' , substantially as and for the purpose set forth. 120 125

6. In an emery grinding-machine, the combination of a fixed support having the raising and lowering top B' and fixed part B , provided with an opening s extending through them, a power-shaft carrying a driving-pulley below the opening s a rotatory support on the top B' , about the opening s , and a series of horizontally and radially disposed spindles journaled on the rotatory sup-

port, carrying toward their outer ends grinding-disks and toward their inner ends belt-pulleys G' and adapted to be separately brought into operative position in line with the driving-pulley by turning of the rotatory support, and to be connected in turn at their pulleys G' by a belt H to the driving-pulley, and a support l , mounted upon the part B , to extend near the operative position of the spindles at their inner ends, whereby the lowering of the top B' produces slackening of the belt on a pulley G' , so that the belt may be transferred to the support l , and raising of the top B' , when the belt is on a pulley G' , produces tightening of the belt, substantially as and for the purpose set forth.

7. In an emery grinding-machine, the combination, with the fixed support A , having the stationary top B , driving-pulley C^2 , below the top B , belt H , stationary belt-support l

and rotatory support E , carrying horizontally and radially disposed spindles G , provided with grinding-disks and belt-pulleys G' , of the raising and lowering foundation B' for the rotatory support, hinged toward one edge 25 to the top B , the rock-shaft m , journaled in the support A and carrying one or more cams m^2 , upon which the part B' rests toward its edge opposite the hinged edge, and belt-shifting mechanism I , comprising a crank- 30 arm k , fixed to the rock-shaft m , rod k' , and sliding frame i , carrying belt-engaging pins i' , whereby rocking of the shaft m produces alternate raising and lowering of the part B' and support E and shifts the belt, substantially as and for the purpose set forth.
